UNITED STATES PATENT OFFICE.

OTTO H. ESCHHOLZ, OF WILKINSBURG, PENNSYLVANIA, ASSIGNOR TO WESTINGHOUSE ELECTRIC & MANUFACTURING COMPANY, A CORPORATION OF PENNSYLVANIA.

ARC-EXTINGUISHING DEVICE.

Application filed February 20, 1922. Serial No. 537,857.

To all whom it may concern:

Be it known that I, Otto H. Eschholz, a citizen of the United States, and a resident of Wilkinsburg, in the county of Allegheny and State of Pennsylvania, have invented a new and useful Improvement in Arc-Extinguishing Devices, of which the following is a specification.

My invention relates to arc-extinguishing devices and particularly to the arcing horns of electric switches.

My invention has for its object the provision of arcing horns of such form that, as the arc is moved away from its point of establishment, under the influence of blow-out coils or otherwise, gradually increasing resistance is introduced between the arc terminals and the spaced switch terminals and the arc stream thereby rendered unstable.

20 The single figure of the drawing illustrates, partially in side elevation and partially in section, a pair of switch members and an arc chute to which my invention is applied.

25 I provide a pair of relatively movable contact members 1 that may be mounted in any manner desired. The contact members 1 are provided with arcing horns 2 and 3 that are disposed between side walls 4 of an arc chute.

30 Pole pieces 5 are provided on the exterior of the walls 4; the pole pieces and a side wall of only one side of the arc chute being illustrated in the drawing. It will be understood, however, that these parts may be of any usual form and that a blow-out coil 6 is provided for setting up a flux across the path of an arc that travels upwardly along the arcing horns 2 and 3 from the contact members 1, when such contact members are being separated.

40 The arcing horn 2 is composed of sections 7 and 8 that are secured together, but insulated from each other by means of a member 9. A resistor 10 bridges across the space between the sections 7 and 8.

The arcing horn 3 is composed of sections 12 and 13 that are insulated by means of a block 14 and are connected electrically by resistance member 15.

50 Upon the separation of the contact members 1, an arc is formed adjacent to their upper ends, and, under the influence of the magnetic blow-out apparatus, as well as its natural tendency to rise, such arc is caused

to travel upwardly along the horns 2 and 3 until it reaches the point 17. The arc will then form across the sections 8 and 13 and will continue its upward movement, as indicated by the dotted line 18.

It will be observed that the lower ends of the sections 8 and 13 overlap the upper ends of the sections 7 and 12 so that the arc may readily pass from the lower sections to the upper sections and that, when the arc has passed to the upper sections, the circuit of which it forms a part includes the resistance elements 10 and 15, thus reducing the energy developed by the arc as well as the arc current, thereby more readily effecting the rupture of the arc.

70 It is, of course, well known that, as the length of the arc stream increases on an approximate constant potential circuit, its stability decreases, because of the increased resistance thereof and consequent decreased arc current.

75 By my form of construction, the necessity for the employment of splitters or deflectors, such as are sometimes utilized for increasing the length of the arc stream within a limited space, is avoided, inasmuch as I do not depend wholly upon an increasing length thereof for the breaking down of the arc and dissipation of stored circuit energy.

80 It will be apparent that, instead of making the horns 2 and 3 of only two sections each, they may be made in as many sections as desired, with insulation and resistance interposed therebetween, in the manner illustrated. Furthermore, it will be understood that, instead of the coils 10 and 15, I may employ bars of relatively great resistance material having a high positive co-efficient of resistance which may also serve as supports for the sections of the horns.

85 Various other modifications may be made without departing from the spirit and scope of the invention, as set forth in the appended claims.

100 I claim as my invention:

1. The combination with a pair of relatively movable contact members, of two arcing horns each composed of a plurality of sections that are spaced longitudinally and connected by blocks of insulating material.
2. The combination with a pair of relatively movable contact members, of two arcing horns each composed of a plurality of

sections that are spaced longitudinally, the spaced sections of each horn being insulated from each other and connected by resistance elements.

5. The combination with a pair of relatively movable contact members, of arcing horns of a predetermined increasing resistance toward their extremities.

4. The combination with a pair of relatively movable contact members, of two arcing horns each of which is composed of longitudinally disposed sections that overlap at their adjacent ends.

5. The combination with a pair of relatively movable contact members, of two arcing horns each of which is composed of longitudinally disposed sections that overlap at their adjacent ends and are connected by resistance members.

6. The combination with a pair of current

conductors across which arcs may form under predetermined conditions, of means for moving the arc terminals along a pair of relatively movable and separable auxiliary conducting members to a point remote from the said conductors, one of the said conducting members being formed in sections that are connected by a resistance member.

7. The combination with a pair of relatively movable current conductors across which arcs may form under predetermined conditions, of a pair of relatively movable arcing horns carried by and insulated from the conductors, one of which is connected to one of the conductors by a resistance element.

In testimony whereof, I have hereunto subscribed my name this 15th day of February, 1922.

OTTO H. ESCHHOLZ.
